UNITED STATES PATENT OFFICE.

MYRON H. DISBROW, OF ROCHESTER, NEW YORK.

BASKET.

SPECIFICATION forming part of Letters Patent No. 353,352, dated November 30, 1886.

Application filed April 14, 1886. Serial No. 198,873. (No model.)

To all whom it may concern:

Be it known that I, MYRON H. DISBROW, a citizen of the United States, residing at Rochester, in the county of Monroe and State of New York, have invented certain new and useful Improvements in Berry or Fruit Baskets; and I do hereby declare the following to be a full, clear, and exact description of the invention, such as will enable others skilled in the art to which it appertains to make and use the same.

The object of my invention is to supply a demand for berry-baskets of greater capacity than those now generally made, that will interchangeably fit crates made for the present standard sizes.

To this end, and in order that each basket may be conveniently handled and carried, my invention consists in the combination, with an oblong basket of an exact multiple in length and capacity of a standard fruit-basket, of two wire bails or handles corresponding in form and dimensions with the contour of the end portions of the baskets, pivotally connected with the sides of said basket about one-third of its length apart, for steadiness in carrying, and so that they may be folded or turned down and rest on the rim or edge of the basket and not occupy any appreciable space.

In the drawing, the figure is a perspective, showing my improved berry-basket.

A is the body of an oblong basket, made of the same depth and width but just double the

length and capacity of an ordinary standard-measure basket. Such basket without a handle is awkward in use. If provided with a rigid handle, it will not pack closely, and a single pivoted bail will not secure steadiness in handling. I therefore combine with such basket two bails or handles, B B, by pivotally connecting them with the sides of said basket at points about one-third of its length apart, as shown. These bails or bows are made of the same shape and dimensions as the edge or rim of the ends of the basket and fold or turn down and rest thereon when packed in crates.

I am aware that it is not new to attach two bails or handles which swing past the edge to lunch or other similar baskets, and such I do not claim; but

What I do claim, and desire to secure by Letters Patent, is—

A berry-basket consisting of the combination, with an oblong body or receptacle, of two wire bails or handles corresponding in form and dimensions with the contour of the end portions of the basket, pivotally connected with the sides of said basket about one-third of its length apart, substantially as described.

In testimony whereof I affix my signature in presence of two witnesses.

MYRON H. DISBROW.
